UNITED STATES PATENT OFFICE.

JOHN S. REESMAN, OF HIGHLAND PARK, ILLINOIS.

CLOTHES-PIN HOLDER.

1,214,367.

Specification of Letters Patent. Patented Jan. 30, 1917.

Application filed November 28, 1914, Serial No. 874,478. Renewed November 25, 1916. Serial No. 133,493.

To all whom it may concern:

Be it known that I, JOHN S. REESMAN, a citizen of the United States, residing at Highland Park, in the county of Lake and 5 State of Illinois, have invented new and useful Improvements in Clothes-Pin Holders, of which the following is a specification.

The present invention relates to a clothes pin holder wherein use is made of a bag 10 which is removably suspended from the clothes line for holding the clothes pins in convenient reach of the user of the same.

The primary object of the invention resides in the provision of a hanger for the 15 bag, of novel construction whereby both the front and rear walls of the bag are supported to prevent sagging of the same under the weight of the contents of the bag and to hold the mouth of the latter spread to facilitate the insertion of the pins into the 20 bag or their removal therefrom.

The figure in the drawing is a perspective view of my invention, the bag being partly 25 broken away to show the construction of the hanger.

Referring more particularly to the drawing 5 designates the bag constructed from cloth or other suitable flexible material, and comprises two pieces 6 and 7 stitched along 30 their marginal edges and forming what may be termed "front and rear" walls of the bag. As shown each piece of material is substantially square, the front wall 6 being cut away longitudinally from its upper edge to 35 provide an enlarged substantially square opening 8 constituting the mouth of the bag, while the rear wall 7 forms a backing for the opening 8 to direct the pins into the bag. With a bag constructed in the above de- 40 scribed manner, I employ a hanger 9 forming the subject matter of my invention, for supporting the bag upon the clothes line in convenient reach of the user of the device. As shown the hanger is formed from a sin- 45 gle length of wire to provide a substantially rectangular frame 10 to conform to the configuration of the opening 8, the parallel portions 11 and the lower cross bar 12 being received within the hems 13 formed by the 50 marginal edges of the opening 8. The parallel portions 11 terminate in oppositely dis- posed lateral extensions 14, which are bent upwardly as at 15 and thence downwardly as at 16 defining the line receiving hooks 17, 55 the wire being bent upon itself in the for-

mation of the hook and extended transversely to provide the upper bar 18 of the rectangular frame 10, with the hook portions on said bar contacting with the hook portions on the other bar throughout their 60 length to prevent the sagging of the bar under the weight of articles placed within the bag. The free ends of the wire can be soldered or otherwise suitable secured. The upper bar 18 is received within the hem 19 65 formed by the upper edge of the rear wall 7, the latter being thus independently supported so that the strain on the frame due to the weight of the contents of the bag will be distributed between the bars 12 and 18 70 respectively. By reason of this construction, it will be further obvious that both the front and rear walls of the bag are prevented from sagging under the weight of the 75 contents thereof, and that the mouth of the bag is reinforced and held open under all conditions to permit ready access to be had to the bag.

It is believed that from the foregoing description the nature and advantages of the 80 invention will be readily apparent without requiring a more extended explanation and therefore the same has been omitted.

What I claim is:—

The combination with a bag having a sub- 85 stantially square opening at the upper edge thereof, of a hanger constructed from a strand of wire looped above said opening to provide two horizontally extending sides contacting for a portion of their lengths at 90 opposite ends of the loop with one of said sides connected with the top of the bag, the other of said sides being bent between the contacting portions to provide a downwardly extending U-shaped frame secured 95 to the sides and bottom of the opening, said contacting portions being bent between their ends to provide upwardly extending hooks with the hook portions on the straight side of the loop bearing against the inner faces 100 of the hook portions on the bent sides of the loop throughout their length, to prevent the sagging of the sides of the loop under the weight of articles placed within the bag.

In testimony whereof I affix my signature 105 in presence of two witnesses.

JOHN S. REESMAN.
